UNITED STATES PATENT OFFICE.

CHRISTOPHER W. LEVALLEY, OF ST. PAUL, MINNESOTA.

BOLT AND RIVET CUTTER.

SPECIFICATION forming part of Letters Patent No. 242,142, dated May 31, 1881.

Application filed April 16, 1881. (No model.)

To all whom it may concern:

Be it known that I, CHRISTOPHER W. LEVALLEY, a citizen of the United States, residing at St. Paul, in the county of Ramsey and State of Minnesota, have invented certain new and useful Improvements in Bolt and Rivet Cutters; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 This invention relates to improvements in bolt-cutters of that class having a fixed cutter, a sliding cutter, and toggle-levers to advance the sliding cutter. Its object is to simplify the construction and reduce the weight of 20 metal, and at the same time increase the efficiency of the implement by so constructing the parts that the power shall be centrally applied.

Figure 1 is a side view of a bolt-cutter embodying my improvements. Fig. 2 is a view 25 of the sliding carriage detached. Fig. 3 is a cross-section on the line $x-x$, Fig. 1, looking in the direction of the arrow y . Fig. 4 is an edge view of a somewhat modified form. Fig. 5 is a face view of the cutter shown in Fig. 4.

30 In the drawings, A represents the yoke, in which are mounted the other parts—namely, the fixed cutter, the sliding cutter, and the levers for operating the latter. This yoke is formed with a rectangular centrally-open part, 35 A', having grooves $a-a'$ in the sides of the opening a therein, to serve as ways for the sliding cutter.

B represents the fixed cutter, fastened securely to the part A at the outer end of the 40 opening and near one of the faces of the said part A.

The sliding cutter is represented by C. It is substantially rectangular in cross-section, and is cast with tongues $c-c$ on its sides, adapted to fit the grooves $a-a'$. At the rear end of the cutter-piece there is a screw-threaded socket, within which is fastened a screw-threaded stem, D, carrying a U-shaped stirrup, D'.

45 E E are levers pivoted to the yoke or supporting part A. They are adapted to receive wooden handles, which can be inserted into sockets formed in the outer ends of the levers.

G G are toggle-levers, each pivoted at one end to one of the levers E, and at the other end pivoted within the the U-shaped part D'. They 55 are pivoted to the latter by means of a bolt or screw, which can be readily withdrawn when it is necessary to sharpen the cutter or adjust its throw.

In the construction shown in Figs. 1 and 3 60 the yoke part A is formed with an extended part, A^2 , at the inner end, through which there is an aperture for the passage of the sliding cutter. The handle-levers E E are pivoted at their ends to this extended part at $e-e$. The 65 toggle-levers in this case are pivoted to the handle-levers E E by means of inwardly-projecting ears or lugs F F, through which pass pivots $f-f$. These ears F F not only carry the pivots of the toggle-levers, but also act as 70 stops to prevent the handles from being forced too close together.

In the construction shown in Figs. 4 and 5 the yoke part is depressed, as shown at A^3 , and to the inner end of this depressed portion 75 the handle-levers E E are pivoted at points somewhat distant from their forward ends, and the toggle-levers are pivoted at the forward ends of the handle-levers. The toggle-levers, however, in this construction, as in the other, 80 are pivoted on the central line of the cutter by means of the adjusting-screw and stirrup D'. When the cutter is going forward it moves with gradually-decreased speed, but increased power, and this power is all utilized, for the 85 movable parts are all arranged in substantially the same plane.

I am aware that bolt-cutters have been constructed with intermediate levers, each pivoted to one of the handles, and also to the cutter-carriage, and I do not broadly claim such constructions as my invention; but in the cutters with which I have been acquainted the intermediate levers have been pivoted at two or more points to the cutter-carriage, and have 95 been situated in planes other than the central plane of said carriage.

I have found that by arranging the parts as described I can apply the power to much greater advantage than when the levers are pivoted 100 and situated as heretofore.

My device dispenses with much of the metal heretofore used in constructing bolt-cutters of the same general character. A long carriage

has been generally heretofore employed, which I dispense with by pivoting the levers to the adjusting-screw at the rear end of the sliding cutter.

5 5. What I claim is—

1. In a bolt-cutter, the combination of the following elements, namely: the yoke or supporting part A, having the central aperture, a, and the grooves a' a', the cutter C, having 10 the tongues c c, the screw-stem D, engaging with the sliding cutter and carrying the U-shaped part D', the toggle-levers G G, connected by a single pivot to said part D', and the levers E E, pivoted to the part A and to 15 the levers G G, as set forth.

2. In a bolt-cutter, the combination of the

following elements, namely: the yoke part A, having a central opening and the grooves a' a', the levers E E, pivoted to the yoke and formed with the lugs F F on their inner sides, the cutter C, having the tongues c c, the screw-stem D, carrying the U-shaped stirrup D', and the toggle-levers G G, pivotally connected to said stirrup on the central line of the part C, as set forth.

25 In testimony whereof I affix my signature in presence of two witnesses.

CHRISTOPHER W. LEVALLEY.
